UNITED STATES PATENT OFFICE.

OLAF M. GORDER, OF ZUMBROTA, MINNESOTA.

BOBSLED.

1,413,299.

Specification of Letters Patent. Patented June 6, 1922.

Application filed January 7, 1921. Serial No. 485,617.

To all whom it may concern:

Be it known that I, OLAF M. GORDER, a citizen of the United States, residing at Zumbrota, in the county of Goodhue and State of Minnesota, have invented certain new and useful Improvements in Bobsleds; and I do hereby declare the following to be a full, clear, and exact description of the invention, such as will enable others skilled in the art to which it appertains to make and use the same.

My invention relates to improvements in bob sleds and has for its object to provide means whereby a standard width bob sled may be increased in width so that it will track with automobiles or other vehicles of standard width.

To the above ends, generally stated, the invention consists of the novel devices and combination of devices hereinafter described and defined in the claim.

In the accompanying drawings, which illustrate the invention, like characters indicate like parts throughout the several views.

Referring to the drawings:

Fig. 1 is a perspective view of the bob sled having the invention embodied therein;

Fig. 2 is a fragmentary detail view in side elevation with some parts sectioned on the line 2—2 of Fig. 3;

Fig. 3 is a fragmentary elevation with some parts sectioned on the line 3—3 of Fig. 2;

Fig. 4 is a fragmentary plan view with some parts sectioned on the line 4—4 of Fig. 1; on an enlarged scale;

Fig. 5 is a plan view of certain of the parts shown in Fig. 4; and

Fig. 6 is a detail view principally in section taken on the line 6—6 of Fig. 4, with some parts indicated by means of broken lines.

The bob sled illustrated includes front runners 7, rear runners 8, knees 9, beams 10, bolsters 11, reach structure 12, and pole 13. Rollers 14 connect the rear runners 8 to the rear structure 12 and the front runner 7 to the pole 13. Rearwardly diverging brace rods 15 connect the reach structure 12 and the pole 13 to the respective rollers 14. Tie rods 16 pivotally connect the respective rollers 14 to the front and rear runners. The parts thus far described are of standard construction and width.

The knees 9 have wide yoke-like transverse portions 17 which, in standard construction, are rockably seated in longitudinally extended grooves 18 formed in the under faces of the beams 10 and are connected to said beams by U-shaped bolts 19, the arms of which are inserted through vertical bores 20 in the beams 10. Wearing plates, not shown, are customarily interposed between the yoke-like portions 17 of the knees 9 and the beams 10.

Referring now in detail to the means for widening the bob sled so that it will track with automobiles or vehicles of standard width, I remove the runners 7 and 8 from the beams 10 by detaching the U-shaped bolts 19 therefrom and placing, on the ends of

said beams, metallic beam extension caps 21, which, as shown, are rectangular in cross section and project outward thereof. These beam extension caps 21 are horizontally and longitudinally split and detachably, but rigidly, secured to the beams 10 by pairs of bolts 22 inserted through aligned holes therein and the bores 20. By horizontally and

longitudinally slitting the beam extension caps 21, the same may be expanded or contracted to fit beams of different thicknesses. A third bolt 23 is inserted through aligned holes in the beam extension caps 21 and beams 10, inward of the bolts 22, to afford additional means for securing said caps to the beams. Outward of the beams 10, the beam extension caps 21 are provided with vertically aligned pairs of holes to receive the arms of the U-shaped bolts 19 and connect the runners 7 and 8 to said caps. The bottoms of the beam extension caps 21 are inwardly pressed to afford ribs 23 that are

channel-shape in cross section. The inner portions of the ribs 23 are adapted to be seated in the grooves 18, in the beams 10, and the outer portions thereof, are adapted to rockably receive and hold the yoke-shape portions 17 of the knees 9. Preferably, filler bars 24 are placed in the ribs 23 to afford washers for the bolts 22. Obviously, the ribs 23 reinforce the beam extension caps 21 and greatly strengthen the same. The inner arms of the U-shaped bolts 19 afford stops to limit the movement of the beam extension caps 21 onto the beams 10.

To extend the rollers 14 to the increased width between the pairs of runners 7 and 8,

I telescope onto the ends of said rollers, cylindrical roller extension caps 25 and secure the same thereto by nut-equipped bolts 26. Nut-equipped bolts 27, which extend through 5 the intermediate portions of the roller extension caps 25, limit the telescopic movement of said caps onto the rollers 14. These roller extension caps 25 have, in their outer or closed ends, bores through which the tie rods 16 project. It is, of course, necessary to increase the length of the tie rods 16 by welding a piece thereon or substituting 10 longer tie rods for the original ones. The brace rods 15 must also be increased in length in the same manner and preferably, as shown, the rear ends thereof are extended through aligned holes in the outer ends of the roller extension caps 25 and are secured thereto by opposing nuts 28. The roller extension caps 25, at their inner ends, are longitudinally split at diametrically opposite 15 points to permit the same to be expanded so as to fit rollers of varying diameters. In case it is desirable to change the bob sled 20 back to its original or narrow width, the beam extension caps 21 may be left in place,

the bolts 22 removed and the U-bolts 19 substituted therefor.

The above described invention makes it 30 possible to increase the width of a bob sled at a comparatively small cost and with little labor. Certain States have passed laws that make it necessary to increase the width of commercial bob sleds, so that they will track with automobiles or other vehicles of standard width and by the use of my invention, all bob sleds now in use or manufactured 35 having metal knees, may be very easily adjusted to meet the necessary requirements.

What I claim is:—

In a bob sled, the combination with beams, 40 front and rear runners, a pole having a roller and a reach structure having a roller, of beam extension caps secured to the ends of the beams, means connecting the runners 45 to the beam, extension caps outward of the beams, roller extension caps secured to ends of the rollers, and tie rods connecting the pairs of runners and extending through the 50 roller extension caps.

In testimony whereof I affix my signature.
OLAF M. GORDER.
